(57) **CLAIM**

The ornamental design for a speaker console for a motorcycle saddlebag, as shown and described.

DESCRIPTION

FIG. 1 is a perspective view of the left speaker console of the pair of speaker consoles for motorcycle saddlebags, shown in place on motorcycle saddlebags, with a portion of the motorcycle being shown in phantom lines to illustrate the environment of the invention;

FIG. 2 is a front end view of the left speaker console of the pair of speaker consoles for Motorcycle Saddlebags of FIG. 1;

FIG. 3 is a left side view of the left speaker console of the pair of speaker consoles for motorcycle saddlebags of the invention;

FIG. 4 is a right side view of the left speaker console of the pair of speaker consoles for motorcycle saddlebags of the invention;

FIG. 5 is a rear end view of the left speaker console of the pair of speaker consoles for motorcycle saddlebags of FIG. 1;

FIG. 6 is a top view of the left speaker console of the pair of speaker consoles for motorcycle saddlebags of the invention; and,

FIG. 7 is a bottom view of the left speaker console of the pair of speaker consoles for motorcycle saddlebags of the invention.

The right speaker console of the pair of speaker consoles for motorcycle saddlebags is a mirror image of the left speaker console.

The broken lines immediately adjacent the circular speaker openings are boundaries and form no part of the claimed design.
